UNITED STATES PATENT OFFICE.

WILHELM FREH, OF VIENNA, AUSTRIA-HUNGARY.

STICK ADAPTED FOR SELF-DEFENSE.

SPECIFICATION forming part of Letters Patent No. 723,260, dated March 24, 1903.

Application filed August 21, 1902. Serial No. 120,566. (No model.)

To all whom it may concern:

Be it known that I, WILHELM FREH, a subject of the Emperor of Austria-Hungary, residing at Vienna, in the Empire of Austria-Hungary, have invented certain new and useful Improvements in Sticks Adapted for Self-Defense; and I do hereby declare the following to be a full, clear, and exact description of the invention, such as will enable others skilled in the art to which it appertains to make and use the same.

This invention has for its object to enable a walking-stick or an umbrella to be more effectually applied as a means of self-defense. For this purpose a walking-stick or an umbrella (hereinafter referred to as the "stick") is according to this invention provided with a handle of special construction, which while suitable for its usual purpose is also adapted in the event of an attack to serve as a rigid hand-guard, which like that of a sword or saber protects the hand while a blow is being warded off. The stick is, moreover, according to this invention provided with a hilt, which normally is contained within the stick, but which in the event of an attack may be caused to project therefrom and to assume a suitable position for the handle to serve as a hand-guard, as already explained.

This invention is hereinafter described with reference to the accompanying drawings, which illustrate examples of apparatus in accordance therewith. This fundamental idea can be put into practice in many ways, and consequently the constructional forms shown upon the accompanying drawings are only to be regarded as examples of the defensive stick as defined in the patent claims.

Figure 1 of the said drawings is a longitudinal view of the stick, mainly in section, and with the hilt contained within the stick. Fig. 2 is a plan of the upper side of the handle thereof. Fig. 3 is a view corresponding to Fig. 1, but showing the hilt drawn out, so that the stick is available for self-defense. Figs. 4, 5, and 6 are views of details of the stick shown in Figs. 1 and 3. Figs. 7 and 8 show in longitudinal section modifications in accordance with this invention; and Figs. 9 and 10 show in longitudinal section and top plan, respectively, another modification in accordance therewith.

The stick shown in Figs. 1 to 6 comprises a rod *a*, of wood or metal, which is firmly secured to a tube *b* or is formed in one piece therewith. To the upper end of this tube *b* is secured the handle *c*, which is preferably of the form shown, but which may be of any desired form and may in some instances have but one arm. The hilt *d*, with which the stick is according to this invention provided, while normally contained within the tube *b* and the handle *c*, can when desired be released therefrom and firmly held while extending beyond the handle *c*. The stick is then adapted to be used in self-defense and may be held by the hilt *d*, while the handle *c* acts a guard or protection for the hand while warding off hostile blows and thrusts. There is arranged in the tube *b* below the hilt *d* a helical spring *e*, which automatically causes the hilt to spring out when released. In the upper part of one arm of the handle *c* there is formed a slot *f*, which by means of a passage *f'* communicates with a chamber *g*, which contains a spiral spring *h*, acting upon a bolt *i*. In the slot *f* is lodged a catch *i*², which is secured to the upper side of the bolt *i* by means of a connecting-piece *i'*. By means of the catch *i*², the top of which is preferably roughened or fluted, the bolt *i* can be pressed back against the action of the spring *h* in order to release the hilt *d*. In the hilt *d* there are formed two recesses *k'* and *k*², located exactly one above the other, and the bolt *i* is, by means of its spring *h*, caused to engage in one or other of these recesses, according to the position of the hilt. When the hilt is in its normal position, the stick resembles an ordinary walking-stick and is carried in the same manner. In order to admit of its being used as a means of defense, pressure is brought to bear—say with the thumb of the right hand—upon the catch *i*² in the direction of the arrow in Fig. 1. By this means the bolt *i* is, against the action of its spring *h*, withdrawn from the recess *k'*. The hilt *d* being thus released, its end is by the action of the spring *e* caused to project beyond the tube *b* and the handle *c*, and the hilt is then drawn out by hand until its lower recess *k*² is engaged by the spring-bolt *i*. The hilt *d* is thus firmly secured above the guard *c*, and the stick is available for use as a means of defense, as shown in Fig. 3. In a similar manner by

pushing back the catch i^2 the hilt d may be returned to the tube b . In order to prevent the hilt d from rotating within the tube b , so that the recesses k' and k^2 no longer fall exactly in alignment with the bolt i , there may be formed in the handle d a groove d' , which engages either the bolt i or a pin i^3 , Fig. 7, attached thereto. The rotation of the hilt d in the tube b can also be prevented by making the tube b and the hilt d of non-circular cross-section—as, for example, of the oval section shown in Fig. 10.

The catch i^2 may in some instances be lodged in the under side of the guard or handle c , as shown in Fig. 8, instead of in its upper side. In this case the slot f must be cut to a sufficient length in c in order to permit of the movement of i and i^2 .

When, as is preferred, the guard or handle c is provided with two arms, there may in some instances be formed in each arm a chamber g , containing a spring-bolt.

It would of course be practicable to provide in the upper end of the hilt d two recesses k' and to withdraw each bolt from the corresponding recess by means of a catch, such as already described, arranged either upon the upper or the under side of the handle c . Such an arrangement is, however, liable to the objection that in order to eject the hilt d it would be necessary to operate two catches possibly while subject to an attack. In order to obviate this disadvantage, there is shown in Figs. 9 and 10 an arrangement in which, notwithstanding that two bolts are provided, one movement only is required in order to release the hilt d . In this arrangement only the lower recess k^2 is provided in duplicate, and when the stick is not needed for self-defense one of the bolts i^4 is pushed back into its chamber g against the action of its spring h , as shown on the left in Fig. 9, while the other bolt i is engaged in the recess k' . When the hilt d is drawn out, the bolts i and i^4 both engage in the recesses k^2 . Both arms of the handle c thus coöperate to support and firmly hold the drawn-out hilt. When it is desired to return the hilt d to the tube b , the bolts i and i^4 must both of course be suitably released; but when the danger is past there is plenty of time to do this. In Figs. 9 and 10 there is shown by way of example a suitable arrangement for manipulating the bolts i and i^4 . The chambers g , containing the springs h , are in this case both closed on the upper side of the handle by means of plugs c' , through which pass pins connected to the corresponding bolts and provided with heads or catches. The bolt i (shown on the right in Fig. 9) is rigidly connected with a pin l , terminating in a catch l' ; but the bolt i^4 (shown on the left of Fig. 9) has formed therein, as shown, a recess or chamber, in which slides a piston connected to a pin l^2 . This means allows the pin l^2 not to project beyond the handle c when the hilt d is within the tube b , while at the same time

when the hilt has been drawn out and it is desired to return it to the tube the bolt i^4 may by means of the pin l^2 and the knob l^3 thereon be withdrawn from a recess k^2 .

The devices employed for effecting the release of the hilt d and its return to the tube b may in practice be considerably modified, and consequently the scope of this invention is not to be regarded as restricted to the precise arrangements herein set forth.

Having thus described the nature and objects of my invention, what I claim as new, and desire to secure by Letters Patent, is—

1. A walking-stick having means whereby it may be converted into a weapon of defense to be used like a sword, said stick comprising a tubular part, a handle extending laterally in respect thereto, a supplemental part sliding in the tubular part and adapted to be withdrawn to serve as a handle while the handle proper serves as the guard thereto and means for holding the supplemental handle in position against movement in either direction when the said supplemental part is drawn out for use of the device as a sword, substantially as described.

2. A stick adapted for use as a means of self-defense, comprising in combination a main part having a tubular upper end portion; a handle fixed to the top of the main part and adapted to serve as a hand-guard when the stick is applied in self-defense; an adjustable part normally contained within the said tubular portion and handle but adapted to be partially withdrawn therefrom into a position in which it will be suitable to serve as a hilt; means for securing the said adjustable part in the said position; and a spring adapted, when the said adjustable part is released, to eject the said adjustable part partially from the said tubular portion and handle.

3. A stick adapted for use as a means of self-defense, comprising in combination a main part having a tubular upper end portion; a handle fixed to the top of the main part and adapted to serve as a hand-guard when the stick is applied in self-defense; an adjustable part normally contained within the said tubular portion and handle but adapted to be partially withdrawn therefrom into a position in which it will be suitable to serve as a hilt; and a spring-bolt adapted to engage in a recess in the said adjustable part so as to secure it in the said position.

4. The combination in a stick of a main part having a tubular upper end portion, an adjustable part or hilt adapted to be contained within the said tubular portion, and to be partially withdrawn therefrom, and provided near its upper and lower ends with recesses; a handle secured to the said tubular portion and adapted to serve as a hand-guard; means for automatically engaging in the said recesses to hold the said adjustable part in each of its two end positions; and a spring adapt-

ed, when the said adjustable part is released, to eject the said adjustable part partially from the said tubular portion and handle.

5. The combination in a stick of a main part having a tubular upper end portion, an adjustable part or hilt adapted to be contained within the said tubular portion, and to be partially withdrawn therefrom, and provided near its upper and lower ends with recesses; 10 a handle secured to the said tubular portion and adapted to serve as a hand-guard; means for automatically engaging in the said recesses to hold the said adjustable part in each of its two end positions; means located at the 15 surface of the said handle for disengaging the said adjustable part; and a spring adapted, when the said adjustable part is released, to eject the said adjustable part partially from the said tubular portion and handle.
- 20 6. The combination in a stick of a main part having a tubular upper end portion, an adjustable part or hilt adapted to be contained within the said tubular portion, and to be partially withdrawn therefrom, and provided 25 near its upper and lower ends with recesses; a handle secured to the said tubular portion and adapted to serve as a hand-guard; means for automatically engaging in the said recesses to hold the said adjustable part in each 30 of its two end positions; means for preventing the said adjustable part from rotating in relation to the said tubular portion; and a spring adapted, when the said adjustable part is released, to eject the said adjustable part 35 partially from the said tubular portion and handle.

7. The combination in a stick of a main part having a tubular upper end portion, an adjustable part or hilt adapted to be contained 40 within the said tubular portion, and to be partially withdrawn therefrom, and provided near its upper and lower ends with recesses; a handle secured to the said tubular portion and adapted to serve as a hand-guard; means

for automatically engaging in the said recesses to hold the said adjustable part in each of its two end positions; means located at the surface of the said handle for disengaging the said adjustable part; means for preventing the said adjustable part from rotating in relation to the said tubular portion; and a spring adapted, when the said adjustable part is released, to eject the said adjustable part partially from the said tubular portion and handle. 45 50

8. The combination in a stick adapted for self-defense, of a main part having a tubular upper end portion; a two-armed handle secured to the said tubular portion and adapted to serve as a hand-guard; two spring-bolts 60 located respectively in the two arms of the said handle; an adjustable part suitable to serve as a hilt and adapted to be contained within the said tubular portion and to be partially withdrawn therefrom, and furnished 65 near its lower end with two recesses adapted to be entered by the two said bolts respectively, and at its upper end with only one recess adapted to be entered by one of the said bolts; means for insuring that the said recesses will come opposite to the said bolts respectively when the said adjustable part is moved longitudinally; releasing devices, one rigidly connected to the bolt for engaging in 70 two recesses and the other having a sliding connection with the other of the said bolts; and a spring adapted, when the said adjustable part is released, to eject the said adjustable part partially from the said tubular portion and handle. 75 80

In witness whereof I have hereunto signed my name, this 5th day of August, 1902, in the presence of two subscribing witnesses.
